DESIGN FOR TEXTILE MATERIAL OR THE LIKE

Joseph C. Janelunas, Brooklyn, N. Y.

Application March 11, 1946, Serial No. 127,337

Term of patent 14 years

(Cl. D92—1)

To all whom it may concern:

Be it known that I, Joseph C. Janelunas, a citizen of the United States, residing in the Borough of Brooklyn, county of Kings, city and State of New York, have invented a new, original, and ornamental Design for Textile Material or the like, of which the following is a specification, reference being had to the accompanying drawing, forming part thereof.

On the drawing, the figure is a plan view of a piece of textile material, showing my new design.

A design unit is outlined by the dot-and-dash lines; the unit repeats over the textile material, as indicated by the extensions of the dot-and-dash lines beyond the unit boundaries.

While the design disclosed herein is shown applied to textile material or the like, it obviously may be applied to other materials, as, for example, paper and the like.

I claim:

The ornamental design for textile material, or the like, substantially as shown and described.

JOSEPH C. JANELUNAS.
